W. WHITSEL.
ICE CREAM TUB.
FILED APR. 26, 1921.

William Whitehead.

Fig. 7. Inventor
William Whiteel.
Massachusetts.
By Attorney.

UNITED STATES PATENT OFFICE.

WILLIAM WHITSEL, OF OSKALOOSA, IOWA.

ICE-CREAM TUB.

Application filed April 26, 1921. Serial No. 464,721.

To all whom it may concern:

Be it known that I, WILLIAM WHITSEL, a citizen of the United States of America, and resident of Oskaloosa, in the county of ⁵ Muscatine and State of Iowa, have invented certain new and useful Improvements in Ice-Cream Tubs, of which the following is a specification.

This invention relates to tubs and particularly to tubs for use in connection with ¹⁰ the manufacture of storage of ice cream.

The invention has for its object the provision of a tub having a relatively strong bottom, the said bottom being provided with ¹⁵ means to permit the circulation of air, in order to prevent undue expansion due to the accumulation of water in the wood forming body.

It is a well known fact that ice cream tubs ²⁰ are subjected to rough usage and abuse and they speedily deteriorate. It is an object of the invention to produce a tub of the character indicated comprising a plurality of staves and hoops supplied with a double bottom fitting in different chime grooves.

It is the purpose of this invention to produce a bottom comprising two thicknesses of wood, as stated, the said bottom sections being held in contact by reason of their ³⁰ mounting in the staves, and it has been found in practice that the two sections retain moisture if kept in contact, whereas a bottom comprising a single piece of the same thickness of the double bottom will dry quicker than a two-piece bottom, a condition which results in the loosening of the joints and the impairment of the tub.

With the foregoing and other objects in view, the invention consists in the details ⁴⁰ of construction, and in the arrangement and combination of parts to be hereinafter more fully set forth and claimed.

In describing the invention in detail, reference will be had to the accompanying ⁴⁵ drawings forming part of this application wherein like characters denote corresponding parts in the several views, and in which—

Figure 1 illustrates a sectional view of a ⁵⁰ tub embodying the invention;

Figure 2 illustrates a sectional view at right angles to the section shown in Fig. 1;

Figure 3 illustrates an elevation of a fragment of a tub at the bottom;

Figure 4 illustrates a similar view of the ⁵⁵ upper fragment of the tub;

Figure 5 illustrates an underneath plan view of the upper section of the bottom of the tub;

Figure 6 illustrates a plan view of the ⁶⁰ lower section of the bottom of the tub;

Figure 7 illustrates an enlarged detailed sectional view of the drain pipe and bushing; and

Figure 8 illustrates an enlarged detailed ⁶⁵ sectional view of the handle.

In these drawings 10 denotes a plurality of staves which may be of any number desired, the said staves being held together by hoops 11 which may likewise be increased or diminished in number, according ⁷⁰ to the strength to be imparted to the tub.

The interior of the tub has chime grooves ⁷⁵ 12 and 13, the former of which forms a seat for the lowermost section 14 of the bottom, the edge of which is beveled to the contour of a wall of the chime groove 12, and the latter of which forms a seat for the upper section 15 of the bottom, which section has a beveled edge shaped to the contour of a ⁸⁰ wall of the chime groove 13.

The upper face of the section 14 has a transversely disposed groove or slot 16, and the upper section 15, in the present embodiment of the invention, has preferably a ⁸⁵ plurality of transversely disposed grooves or slots 17 in its under face, and the said sections are placed in the chime grooves in a manner to insure the contact of the upper surface of the section 14 with the lower ⁹⁰ surface of the section 15, and the groove in the section 14 is at right angles to the grooves 17 although the angles of intersections of these grooves may be changed.

The main purpose, however, in having these ⁹⁵ grooves cross each other is to effect a circulation of air which is admitted between the two sections of the bottom, by reason of the fact that the lowermost hoop 11 has apertures such as 18 which align or register ¹⁰⁰ with apertures 19 formed in the staves, and the said apertures in the staves in turn register with the slot or groove 16 in the lower section of the bottom. It follows from the foregoing, that air may therefore ¹⁰⁵ pass between the sections from one side of the tub to the other, a condition which results in preventing undue accumulation of

moisture in the bottom and any unequal expansion or swelling of the bottom which would result from its being water-soaked. This construction will furthermore prevent the bottom from rotting, as it will prevent the retention of water in the bottom when the tub is not in use.

The inventor has found that a tub made in accordance with the invention, the upper section of the bottom retains the contents of the tub, whereas the ventilating spaces relieve the tub of seepage. The lowermost section of the bottom also braces the upper section and serves to assist in resisting the inside load pressure which is often very great, especially when the tub is being shipped or handled during its transfer. Tubbs of this character are often dropped when being pulled from a conveyance to a sidewalk, station, platform or the like, and as the lowermost section of the bottom is flush with the lower ends of the staves, the staves and bottom present a smooth surface from the lower edge of the bottom hoop to any side across the staves and bottom.

In providing means for draining the tub, the flanged tube 20 is employed, which extends through a threaded aperture 21 in the staves, the said tube being anchored in place by reason of the threads 22 formed on its outer surface. The outer surface of the tub is preferably recessed, as shown at 23, to form a seat for the flange 24 of the tube, as by this arrangement, no projection is afforded which might interfere with the proper packing or handling of the tub. The tube 22 aside from its being threaded in the staves is also secured at its inner end by a ring nut or washer 25 threaded on the tube and bearing against the inner surface of the tub. It is a well known fact that when drain plugs are applied to or removed from unprotected tubs, the wood forming the tub is soon bruised and caused to disintegrate, making it necessary to more tightly drive the plug practically with each of its applications to the drain aperture.

50 A bushing 26 of non-corrosive material is inserted in the tube with its outer end preferably flush with the outer end of the tube and said bushing is shorter than the tube to which it is applied, but preferably this bushing is secured in place by threads 27. The purpose of having the bushing relatively short is to permit the plug or stopper to be oscillated sidewise while it is being loosened for removal. As the bushing is relatively short, lateral impact on the outer end of the plug or stopper would result in a slight lateral movement in the bushing, and when this is repeated several times, the stopper will become dislodged. 65 By reason of the fact that the bushing is

screwed in place, it can be readily removed for the purpose of substituting a new one, and hence the tub can be maintained at a high degree of efficiency with respect to its draining facilities without impairing the 70 tub structure as a whole.

The handle which is employed in connection with the tub preferably comprises a plate 28, which is inserted or set in a recess formed in the stave or staves. A handle 75 pindle 29 has its upper surface shouldered, as shown at 30, and the said pindle has straight sides 31^a and a curved lower side 31^b. The handle 31 is of the ordinary loop type and it has an aperture 32 to receive the pindle, the wall of the aperture at the upper side having a longitudinal recess or seat to allow the handle to seat on the pindle. The fact that the handle when swung into the housing has a slot or recess which permits 85 the handle to fall or descend until the pindle lies in the said seat or recess, results in the retention of the handle in its folded position against swinging outwardly as the tub is handled, although, of course, by a slight 90 lifting action on the handle, it can be unseated from the pindle and it is then free to swing to the horizontal position shown in dotted lines (Fig. 8).

The plate 28 has a depending flange 28^b 95 at its front edge near the top which is intended to engage the handle when it is swung outwardly, and the inner end of the handle beyond the pivot, engages shoulders or lugs 28^a formed on the face of the plate, 100 and the said flange and lug serve to support the load and remove the load from the pin or pindle, a condition which results in durability.

As shown in the drawing, the plate 28 has 105 a marginal flange A which extends around its edge and it is to be set in a recess formed in the outer surfaces of the staves, in order that the outer faces of the flanges will be flush with the outer faces of the staves to 110 permit the hoops to be applied to the tub by passing over the surfaces of the flanges.

It will be noted that the handles and the drain plug shown and described herein are particularly adapted for use with a receptacle of the character set forth, as the handles are held in place by the hoops, said handles being seated in recesses in the staves, also that the drain tube is flush with the staves and is positioned between the lower 115 hoops, to be protected by the same. These features of my invention will form the subject matter of other applications for Letters Patent.

I claim:

1. In an ice cream tub, a body comprising staves and members for holding the staves together, a double bottom in interlocking engagement with the staves, the said sections of the double bottom having their surfaces 120

in contact and having ventilating passages therebetween, and the said staves having passages communicating with the passages between the sections of the double bottom.

5. 2. In an ice cream tub, a body having superposed chime grooves near its lower ends, a sectional bottom in the said chime grooves, the said sectional bottom having ventilating passages therebetween, and at least one of said ventilating passages being in communication with the atmosphere through the body of the tub.

10. 3. In an ice cream tub, a body comprising staves and hoops, the said body and the lowermost hoop having coinciding apertures, the said body having chime grooves in superimposed relation in its inner surface near the lower end, a sectional bottom, the sections of which have their edges seated in the

20. chime grooves, the said sections having air

passages therebetween, at least one of said air passages being in communication with the aforesaid apertures.

4. As an improved article of manufacture an ice cream tub, comprising staves having a double chamfer adjacent to their lower ends, a bottom formed of inner and outer members the margins thereof being seated in said chamfers, an opening through staves located above the bottom and circumscribed 25 by a recess in which is seated flanges of a drain plug, a hoop which encircles the lower end portions of the staves, a hoop located 30 slightly above the drain plug, a pair of handle carrying frame seated to lie in recesses formed adjacent to the upper portion of the staves and spaced hoops which overlie the upper and the lower edges of said handle frames, substantially as shown.

WILLIAM WHITSEL.
